UNITED STATES PATENT OFFICE.

ALBERT SCHOENHUT, OF PHILADELPHIA, PENNSYLVANIA.

DESIGN FOR A TOY FIGURE.

SPECIFICATION forming part of Design No. 36,917, dated May 17, 1904.

Application filed April 12, 1904. Serial No. 202,819. Term of patent 14 years.

To all whom it may concern:

Be it known that I, ALBERT SCHOENHUT, a citizen of the United States, residing in Philadelphia, Pennsylvania, have invented a new, 5 original, and ornamental Design for a Toy Figure, of which the following is a specification.

My design for a toy figure is fully shown in the accompanying drawings, in which—
10 Figure 1 is a front elevation of the figure, and Fig. 2 is a side elevation of the same.

I claim—

The ornamental design for a toy figure substantially as shown in the accompanying drawings.

ALBERT SCHOENHUT.
